UNITED STATES PATENT OFFICE

EDWIN FITCH NORTHRUP, OF PRINCETON, NEW JERSEY, ASSIGNOR TO AJAX ELECTRO-THERMIC CORPORATION, OF AJAX PARK, NEW JERSEY, A CORPORATION OF NEW JERSEY

ELECTRIC INDUCTION FURNACE

Application filed November 23, 1929. Serial No. 409,315.

My invention relates to economy in the use of condensers in carrying on operations in a plurality of furnaces whose power factor the condensers are intended to correct.

5 The purpose of my invention is to shift a main bank of condensers from one furnace to another to afford power factor correction where the greater condenser need occurs, maintaining the power factor correction of 10 the other furnace or furnaces by less condenser capacity, preferably constantly located across the condenser circuits.

A further purpose is to apply the same capacity to local power factor correction at 15 will of any of a pair or a group of furnaces.

Further purposes will appear in the specification and in the claims.

My invention relates both to the processes or methods involved and to apparatus by 20 which the processes or methods may be carried out.

In the drawings I have illustrated but two 25 applications of my invention, presenting the same form but applied respectively to a pair of furnaces and to a group of furnaces. From among various arrangements which could be utilized to carry out my invention I have selected the practical and effective form primarily because of its excellence in illustrating the principles of my invention.

30 Figures 1 and 2 are diagrammatic illustrations of the application of my invention which are identical except that Figure 2 shows the application of the invention to a larger number of furnaces than are seen in Figure 1.

In the drawings similar numerals indicate like parts.

The furnace coils 5 and 6 in Figure 1, 40 are intended to illustrate the operating coils of inductive electric furnaces of any type in which power factor correction is effected by the use of condensers.

The inductor coils only of these furnaces 45 are shown for the reason that my invention concerns the supply of current to and resonance of these coils under different operating conditions and is not affected by other furnace constructions and arrangements except 50 as these affect the coils. The coils are fed

from supply lines 9 and 10 through any suitable connections by which the current can be applied across the desired number and location of turns of the coil, and by which the span of the power input connections may 55 be varied as needed.

The connection is effected in the illustration by applying the current to the coil terminals 11, 11', at one end, and to taps illustrated as 12, 13, 14, 15, 16; 12', 13', 14', 15', 16'; whereby energy supplied to the coil may be varied and the voltage across the terminals of the coils may be correspondingly changed.

In normal operation of individual furnaces of the coreless inductor type, for example, it has been customary to correct the power factor of the furnace inductor by a variable condenser bank such as 17 thrown across the terminals and changed automatically, or by hand, to increase the capacity as the inductance reduces so that the power factor of the current supply for the furnace coils may be maintained substantially at unity. The "tuning" or "resonating" of 70 these coils has involved an equipment of condensers for each furnace capable of taking care of the largest capacity required to resonate the furnace at a minimum furnace coil inductance. 80

It has been proposed, to effect an approximate or average tuning only at the individual furnaces and to apply the remaining capacity for tuning across the current supply for a bank of furnaces, permitting the surplus 85 available capacity of one or more furnaces having leading power factor to be used to assist in resonating the inductance of one or more furnaces having a lagging power factor. While this effects a decided saving in capacity as compared with the total furnace capacity which would be required to individually resonate for the inductance of each individual furnace, the saving has been 90 very much less than can be secured by the present invention.

Applying my invention, therefore, first to the simplest form, to the pair of furnaces shown in Figure 1, I will explain my invention. 100

tion in description and not in limitation as follows:—

The capacity 17 is shown as spanning the terminals of coil 5 and is in parallel with capacity 18, the combined capacities being sufficient to resonate the coil 5 under maximum condenser requirements. It is intended to cooperate with another capacity 18', for example, to resonate the other furnace coil

when its furnace is taking large power input. The condenser capacity 17 is given sufficient range of adjustability to take care of anticipated variations in the inductance of the coil 5 or 6.

For convenience in reference the connections for applying the power input and for including the condensers in parallel will be described as shown, as comprising for any given furnace main switches 19 and 20, conductors 21, 22, 21', 22' therefrom, conductors

23, 24 and 25, 23', 24' and 25' by which the lines are connected with the two ends each of the coils 11, 11' and 26, 26'. The switches 28, 29, 30 and 31 connect the lines with any one of the taps 12 or 12', 13 or 13', 14, or 14', 15 or 15' and 16, or 16'.

Switches 32, 32' permit added inductances 33, 33', to be included or excluded within the path of the corresponding conductors 24 and 25, 24' and 25'.

Switches 34 and 35 provide for application of the capacity 17 alternatively to whatever furnace is to receive large power input, whereby its furnace coil as 5 in the illustrations, will be resonated by the combined capacities whereas the other furnace coil or other furnace coils—whatever their number—are intended to be resonated during this time each by its capacity 18, 18'.

In Figure 2 four furnaces are shown which add additional parts corresponding to the parts of the two furnaces shown including capacities 18², 18³, switches 19², 19³, and 20² and 20³, conductors 21², 21³, 22², 22³, 23², 23³, 24², 24³, 25², 25³ connecting with the ends of the coils at 11², 11³, 26², 26³, and switches 27², 27³, 28², 28³, 29², 29³, 30², 30³ and 31², 31³ by which connection is made to taps 12², 12³, 13², 13³, 14², 14³, 15², 15³, and 16², 16³.

The switches 32² and 33³ permit added inductances 33² and 33³ to be included.

At low power inputs the variation of the input in different furnaces, or at different times and for different operations in the same furnace need ordinarily not vary sufficiently to require that the capacities 18, 18', 18² and 18³ be made adjustable, this being a matter which depends upon the character of the operations performed, the design of the furnace, and the desire or opinion of the designer.

The capacities 17 and 18, 18', 18², 18³ are so proportioned that not only shall the capacity 17 and any one of the 18 group together be sufficient for the maximum capacitive re-

quirements of an individual furnace but that the capacities 18 and 18', etc. shall be sufficient to resonate each its individual furnace coil under conditions of reduced power operation, corresponding for instance to holding the charge, settling, metallurgical treatment or pouring.

The power input for settling or other operations may be but a fourth or a third of that required for melting and major furnace operations. By utilizing added inductance (33, 33', etc.) in series with the corresponding furnace coil during the settling, treating and holding operations within its furnace I am able not only to cut down that part of the voltage from the main power source which is applied to the furnace sufficiently without loss of energy so that the low power input can conveniently be supplied from the same leads but the increase in inductance reduces the capacity required to resonate the circuit, permitting use of small capacities at 18, 18', etc. This determines that the capacities 18, 18', etc., shall be small as compared with the capacity 17.

In operation, the coils of a pair of furnaces, for example, as in Figure 1, are connected as shown in that figure, providing for a melting or superheating operation, let us say, at the left within coil 5 and a metallurgical or holding operation at the right within coil 6.

The system of taps provided may permit wide variation in the actual amount of power input with the application of condenser capacity 17, all for present purposes being classed as major power input connections. In the figure at the left the closing of switch 30³ applies the line voltage across substantially the entire inductor coil, resulting in actual power input considerably below the possible maximum power input with the condenser 17 connected as shown and providing for considerable increase in power by the application of the current at other taps than the tap 15.

Both in what might be called major and minor power input operations the taps permit considerable variation in the actual power input applied. Whatever the tap connections, condensers 17 and 18 together resonate the circuit, which, as will be noted, excludes inductance 33.

In the meantime inductance is added to the furnace coil circuit in each of the other furnaces of the pair or set by inclusion of its corresponding inductance 33', 33² or 33³, which, in the diagram, is effected by operation of its switch 32', 32², or 32³. Each other furnace coil than 5 is then resonated wholly by its individual capacity, which no longer spans the furnace coil alone but spans the furnace coil and added inductance.

The connections of the different furnace coils utilizing low power input have been

shown as bridging different lengths of furnace coil by the use of different taps, merely to show the variation of connection permitted.

5 The application in Figure 2 is identical with that in Figure 1 except that in Figure 2 three furnaces are intended to be operated at a low power input during the time that one furnace is melting.

10 It will be noted that a wide range of flexibility of operation is permissible for each furnace, whether it be connected for high power input or not, and that the ratios of power inputs under different operating conditions may be determined very nicely not only by the size of its individual inductance but by the variant bridging of different proportions of the furnace coils permissible by connection to different furnace taps.

15 20 It will be further evident that the minimum power input in a given furnace with use of capacities 17 and 18 for resonance may approach as closely to the maximum power input, when the capacity 17 is not used, as may be desired in the design of the furnaces by the expedient of increasing the range in variation of power input through 25 tap connection; keeping in mind that the approach of the maximum power input when condensers 17 are omitted to the minimum of power input when condenser 17 is utilized will mean corresponding increase in the capacity of condensers 18 as compared with the capacity of condenser 17.

30 35 It will be further evident that any ratio or proportion desired may be maintained in each individual furnace between the added inductances and the inductance of the furnace coil.

40 45 It will be further evident that application of my invention to furnaces will not interfere with operation of the furnaces in other particulars; that the furnace coil need not be changed from existing coils; and that any other furnace connection may be used as in the case of existing coils having current supply at the voltage applied.

50 It will further be evident that though the furnaces shown in my several figures are in parallel my invention does not depend upon the fact that the furnaces are in parallel.

55 In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

33 Having thus described my invention what I claim as new and desired to secure by Letters Patent is:

60 65 1. The method of operating a plurality of induction electric furnaces and tuning their

coils with a minimum of compensative capacity, which consists in utilizing a main capacity adapted for use, alternatively, with any of the furnaces along with capacity individual to each furnace to make up the complete compensative capacity for a furnace operating under maximum load, shifting the main capacity from furnace to furnace to meet the maximum load conditions of the different furnaces in turn, and at lower loads in the individual furnace in adding inductance to the furnace coil circuit to a sufficient extent for the individual compensative capacity to tune the individual furnaces at these lower loads.

70 75 80 2. The method of tuning a plurality of induction furnaces at maximum and minimum loads with a minimum of compensative capacity, which consists in utilizing condenser capacity individual to the inductors of the several furnaces at all times for compensative capacity, in supplementing this capacity with condensers adapted for use, alternatively, with any of the furnaces, in adding inductance to the inductor circuit of each furnace in turn, as the operating cycle of that furnace requires lower power input, to reduce the voltage applied to the coil and to make it possible for the capacity individual to that furnace to resonate the inductor coil with the added inductance.

85 90 95 100 105 3. The method of operating inductor coil furnaces with a minimum of resonating capacity, which consists in dividing the capacity required for resonance at maximum load in each furnace into two parts, one providing for a major part of the power input and the other for a lesser part of the power input, in shifting the major resonating capacity from one furnace to another so that it is in circuit during times of major input operation of the furnace to which the capacity is shifted, in reducing the capacitative requirements and the voltage effective upon each furnace during the lesser power input requirements by 110 addition of inductance to the circuit and in utilizing the lesser part of the resonating capacity across the furnace and across the added inductance to resonate the furnace coil during operation of the furnace at lower furnace inputs and when the major part of the capacity is being utilized for resonance of another furnace.

115 120 125 4. The method of resonating a furnace coil under conditions of major and minor power input, which consists in utilizing capacities in parallel across the furnace coil for resonance with major power input and in utilizing part of the capacity only across the furnace coil and added inductance to resonate with lesser power inputs.

5. The method of reducing the power input and the capacity required for resonating the inductor coil of an induction furnace, 130 which consists in adding inductance in series

with the inductor coil and in resonating the entire inductance by capacity in parallel with it.

6. A pair of inductor furnaces, power factor corrective condensers common to both furnaces, means for connecting the condensers across the coils of one or other at will, an added inductance, means for adding it to the inductance of the furnace coil of that

10 furnace with which the capacity is not connected, a second capacity and means for connecting the second capacity across said second furnace and inductance.

7. A pair of inductor furnace coils, capacity adapted to be thrown across either coil at will, capacities, one individual to each furnace; adapted to assist in resonating the inductance of the furnace coil at larger loads, and added inductance adapted to be inserted

20 in series with each inductor at lower furnace loads for the purpose of reducing the voltage applied to the furnace and of permitting the individual capacities to resonate the complete inductance at the lower loads.

25 8. An induction furnace having an inductor coil, an inductance in series with the coil and a capacity resonating the circuit embodying the inductor coil and the inductance.

9. In a coreless induction furnace, a furnace coil, a main adjustable power-factor-corrective capacity for the coil, means for applying energy across different coil lengths at will, an added inductance capable of inclusion in series with the coil to reduce the

35 voltage applied to the coil for lower furnace loads and a capacity suited to resonate the inductor coil and added inductance.

10. In a coreless induction furnace, a furnace coil, a main capacity adapted to resonate the coil, an added inductance capable of inclusion in series with the coil to reduce the voltage applied to the coil for lower furnace loads, and a capacity suited to resonate the inductor coil and added inductance, assisting the main capacity to resonate the inductor coil when the added inductance is not used.

11. In a coreless induction furnace, a furnace coil having taps, a main power-factor-corrective capacity for the coil, an added inductance capable of inclusion in series with the coil to reduce the voltage applied to the coil for lower furnace loads, a capacity suited to resonate the inductor coil and added inductance and a source of alternating current supply adapted to span parts of the coil to different taps.

12. In a coreless induction furnace, a furnace coil having taps, a main capacity adapted to largely resonate the coil, an added inductance capable of inclusion in series with the coil to reduce the voltage applied to the coil for lower furnace loads, a capacity suited to resonate the inductor coil and added inductance and assisting the main capacity to

resonate the inductor coil when the added inductance is not used and a source of current for the coil varied by the taps in extent of coil spanned.
